Alan M. Johnson

UNITED STATES PATENT OFFICE.

HENRY B. NEWHALL, JR., OF PLAINFIELD, NEW JERSEY.

HOISTING MECHANISM.

1,288,137.

Specification of Letters Patent. Patented Dec. 17, 1918.

Application filed June 12, 1917. Serial No. 174,217.

To all whom it may concern:

Be it known that I, HENRY B. NEWHALL, Jr., a citizen of the United States, and a resident of Plainfield, in the county of Union and State of New Jersey, have invented certain new and useful Improvements in Hoisting Mechanism, of which the following is a specification, taken in connection with the accompanying drawings.

- 10 My invention relates to hoisting mechanism, and more particularly to an auxiliary hoisting mechanism to be used in connection with a flexible driving member of a more powerful hoisting mechanism.
- 15 More specifically, it relates to an auxiliary device to operate the ordinary chain member of a standard chain hoist. Of course, it is to be understood that while I have shown the flexible member in the form of a chain, any 20 other suitable form of flexible member may be used.

I have shown in the accompanying drawings, different illustrative embodiments of my invention, but of course it is to be understood that my invention is not to be confined simply to the forms illustrated, except as required by the scope of the accompanying claims. In these drawings the same reference numerals refer to similar parts.

- 30 Figure 1 is a side elevation of the ordinary form of standard chain hoist, showing my auxiliary hoisting mechanism coöperating with a hand chain;

Fig. 2 is a side elevation, similar to Fig. 1, except that my auxiliary power member is shown operating the flexible member, or chain, in the reverse direction than that shown in Fig. 1;

Fig. 3 is a side elevation of my auxiliary power member, equipped to coöperate with a flexible member in the form of a hand chain;

Fig. 4 is a vertical section substantially on the line 4—4 of Fig. 5, looking in the direction of the arrows;

Fig. 5 is a plan view of my auxiliary hoisting mechanism, the hand chain being shown in horizontal section, and a portion of the sprocket wheel being broken away for the purpose of clearer illustration.

Large hand power cranes are now in common use in locations where they are not used often enough to warrant the additional expense of installing electric cranes of the

same capacity. For example, in factories, power houses, sugar mills and where it is necessary to replace armatures, dismantle dynamos or turbines, or handle the rolls of a sugar mill, or other heavy part of the operating equipment. These cranes often run as high as fifty tons capacity. They are equipped with the ordinary chain blocks which are operated by a flexible member or hand chain. To operate these heavy cranes often takes a great deal of time, often hours, to hoist an armature, or other similar heavy portion of the equipment, only a few feet, so that the necessary work in connection with, or upon, it may be accomplished. This is on account of the multitude of gear and chain reductions necessary to hoist heavy loads by hand power.

By my invention, with a very slight additional outlay, the ordinary heavy capacity hand crane can be speeded up so that it may be operated ten or fifteen times, or more, faster than it can be operated manually.

In locations where more than one such crane is used my auxiliary hoisting mechanism may be moved from one to another crane performing its work equally well. In cases, where it is not desired to operate it for any reason, it can be readily disconnected and laid aside until such time as it may be desirable to use it again.

85 In the particular embodiment of my invention shown in the drawings, 1, Fig. 3, is my auxiliary power member, formed in the device shown by way of example, by the two side plates 2 and 3, provided with downwardly extending arms 4 and 5, respectively, which are permanently connected together by means of the cross plate 6. On the side plate 2, I secure, in any suitable manner as by the bolts 7, 7, the bearing plate 8, a similar bearing plate 9 being similarly secured upon the side plate 3. Mounted in these bearing plates 8 and 9 is the main axle 10 upon which is keyed the worm wheel 11 and also the chain pocket wheel 12, if my device is to be operated with a flexible member in the form of a hand chain 13. The ordinary hook 41 is mounted on the ordinary load chain 40.

105 Permanently secured upon the cross plate 6 is a driving member 14, which, in the form illustrated, is an electric motor, having a vertical shaft 15 upon which is carried a

worm 16, said shaft being journaled in the cross rods 17 and 18. These rods 17 and 18 have reduced screwthreaded portions 19, 19 to coöperate with the nuts 20, 20 which serve 5 to make the frame rigid.

On the other end of the side plate 3 from the rods 17 and 18, I mount a pivoted yoke 21 on the pivot 22, carried by the plate 23 secured to the plate 3 by the bolts 24, 24.

10 The other end of the pivoted yoke 21 is provided with arms 25, 25 carrying the arbor 26 on which is mounted the idler wheel or sheave 27. This pivoted yoke can be swung about the pivot 22 by grasping the handle 28 so as to bring the idler sheave or wheel in contact with the flexible member 13. The arbor 26 is extended to coöperate with a locking or hook member 29 mounted upon the side plate 2 and operated by the handle 30.

20 In the operation of my device my auxiliary power member 1 is brought over to the standard chain hoist 31 and the pivoted yoke 21 is brought from the position shown in dotted lines in Fig. 5 to full lines in said figure. On light loads my auxiliary power member 1 will remain in the bite 32 of the flexible member or hand chain 13 as shown for example in dotted lines in Fig. 1. On somewhat heavier loads it will partly climb the chain, as shown for example in Fig. 1, wherein the parts are shown in their forward driving position. In reversing the auxiliary power member 1 will fall back into the bite 32 of the chain, or partly climb the other reach of the chain as shown in Fig. 2.

30 To balance the auxiliarily power member, I provide it with some means wherein movable weights, if necessary, may be carried by the said member. I have shown for example, the side frame 2 provided with a hook 33 into which is hooked the rod 34 carrying one or more removable weights 35. 40 The number of the weights may be adjusted for the particular load.

45 The electric motor 14 may be of any capacity but one of one quarter or of three eighths horse power will be ample for all 50 conditions, though of course, this capacity may be varied if found necessary. While I have shown an electric motor it is of course to be understood, that any suitable source of power may be used for driving 55 the worm 16.

Having thus described this invention in connection with an illustrative embodiment thereof, to the details of which I do not desire to be limited, what is claimed as new

and what is desired to secure by Letters Patent is set forth in the appended claims.

What I claim as my invention and desire to secure by Letters Patent is:—

1. In hoisting mechanism, the combination of a main hoisting mechanism operated by a flexible member, and an auxiliary power member supported by the flexible member and adapted to coöperate with the said flexible member to operate the main hoisting mechanism. 70

2. In hoisting mechanism, the combination of a main hoisting mechanism operated by a flexible member, and an auxiliary power member adapted to climb, or tend to climb, the flexible member to operate the 75 main hoisting mechanism.

3. In hoisting mechanism, the combination of a main hoisting mechanism operated by a flexible member, and an auxiliary power member supported by the flexible 80 member and adapted to climb, or tend to climb, the said flexible member to operate the main hoisting mechanism.

4. In hoisting mechanism, the combination of a main hoisting mechanism operated by a flexible member, and a removable auxiliary power member adapted to climb, or tend to climb, the flexible member to operate the 85 main hoisting mechanism.

5. In a hoisting mechanism, the combination of a main hoisting mechanism normally operated by a hand chain, and an auxiliary power member mounted on the hand chain and adapted to operate the hand chain. 90

6. In a hoisting mechanism, the combination of a main hoisting mechanism normally operated by a hand chain, and power means moving with the main hoisting mechanism to operate the hand chain, said power means being adapted to be disconnected from the 100 hand chain.

7. In hoisting mechanism, the combination of a frame, a wheel to engage a flexible member, means to drive said wheel, an idler member to coöperate with the flexible member, and means to support weights on 105 said frame.

8. In hoisting mechanism, the combination of a frame, a wheel to engage a flexible member, means to drive said wheel, an adjustable idler member to coöperate with the flexible member, and means to support 110 weights on said frame.

HENRY B. NEWHALL, JR.
